UNITED STATES PATENT OFFICE.

WARREN H. TAYLOR, OF STAMFORD, CONNECTICUT, ASSIGNOR TO THE
YALE & TOWNE MANUFACTURING COMPANY, OF STAMFORD, CON-
NECTICUT.

MEANS FOR ATTACHING DIAL-LOCKS TO DOORS.

No. 805,039.

Specification of Letters Patent.

Patented Nov. 21, 1905.

Application filed April 13, 1905. Serial No. 255,344.

To all whom it may concern:

Be it known that I, WARREN H. TAYLOR, of Stamford, in the county of Fairfield and State of Connecticut, have invented certain new and useful Improvements in Means for Attaching Dial-Locks to Doors; and I do hereby declare the following to be a full, clear, and exact description of the invention, such as will enable others skilled in the art to which it appertains

10 to make and use the same.

My invention relates to an improved dial-lock. In locks of this class where the lock is secured to the inner face of the door and the dial to the outside it frequently happens, 15 owing to the unequal thickness of the door to which the lock is attached or to carelessness in attaching the parts, the relation between the dial and the tumblers is changed or altered, so that the parts bind or do not work 20 properly.

The object of this invention is to provide a construction of parts that will allow for such irregularities within all reasonable limits and still preserve the proper relation of the 25 working parts of the lock; and it consists in the parts and combination of parts, as will be more fully explained, and pointed out in the claims.

In the accompanying drawings, Figure 1 is 30 a view of the face of the lock, showing the opening for the passage of the dial-spindle. Fig. 2 is a view, partly in elevation and partly in section, showing the dial secured to the lock. Fig. 3 is a view in elevation of the rear 35 face of the dial-ring, and Fig. 4 is a plan view showing the means for locking the screw to the hub.

1 represents a combination-lock of any 40 approved form and construction provided in its face, that rests against the door, with an opening 2 for the passage of the dial-spindle 3. Integral with this lock-casing and surrounding the opening 2 is a nose or projection 4, having diametrically located mortises 5, the 45 said mortises communicating with the spindle-opening 2. This nosing 4 is cylindrical in shape and is designed to project into an opening formed in the door and extends only partly through said door.

50 6 is the dial-ring provided on its outer face with an upturned edge adapted to receive the edge of the dial 7 and provided on its inner face with a sleeve or part having tenons

8, which latter are adapted to rest in the mortises 5 in the nosing 4 and hold the dial-ring 6 and the lock in their proper relative positions and permit of the connection of the parts irrespective of the thickness of the door within, of course, the limits of adjustment of the two parts and irrespective of any irregularities of in the thickness of the door. After the parts have been thus placed and connected they are secured together by screws 9, passing through holes 6^a in the dial-ring 6 and into threaded holes 6^b in the nosing 4 on 65 the lock-case. With this arrangement the dial-ring 6 can readily be placed in its proper position with relation to the tumblers and held there irrespective of the thickness of the door within all reasonable limits.

The ordinary manner of constructing similar locks is to make the nose of the lock-case of sufficient length to extend through the door to which it is to be attached, and the dial-ring is then fastened against and to the 70 nosing by screw-thread or a nut. With such a device the length of the nose must bear a fixed relation to the thickness of the door, whereas with my invention in a lock of the size shown the thickness of the doors may 75 vary to the extent of a quarter of an inch without any alterations in the lock parts. It is of course apparent that the extent of the possible variations may be increased or diminished without departing from the invention.

After the lock-case 1 has been secured to the door and the dial-ring 6 secured to the lock, as explained, the tumbler-carrying gear 10 is placed in position in the lock-case, with its 80 threaded hub 11 in line with the spindle-opening in the nose of the case. The threaded spindle 3, which is fast to the dial 7, is then passed through the dial-ring 6, door, and nose 4, and into the threaded hub 11 and is secured 85 to the latter by rotating the dial. This turning movement of the spindle 3 in the female-threaded hub 11 draws the dial 7 up to the dial-ring 6, and the parts are then secured by driving a key or wedge 13 into grooves formed 90 in the adjacent faces of the spindle 3 and hub 11, the location of these grooves controlling the relative position of the dial and tumblers. After the parts have been thus assembled the tumblers are placed in position and the lock 95 closed by the cap-plate 15. The advantages

of this manner of connecting the dial-ring and lock-case are obvious, and there is the further advantage that if the metal door is not of uniform thickness or if the hole for the nosing 5 is not bored exactly straight the working parts will nevertheless come in proper alignment, by reason of the fact that the screws 9 fasten the dial-ring 6 directly to the lock-case 1. Hence the relation between these two 10 parts is always the same.

It is evident that many slight changes might be made in the relative arrangement of parts herein shown and described without departing from the spirit and scope of my invention. 15 Hence I would have it understood that I do not wish to confine myself to the exact construction of parts shown and described; but,

Having fully described my invention, what I claim as new, and desire to secure by Letters Patent, is—

1. In a dial-lock, the combination with a lock-case having a nose provided with mortises, of a dial-ring having a part provided with tenons to enter said mortises, and screws 25 passing through the ring and into the nose for locking the parts together.

2. In a dial-lock, the combination with a lock-case having a nose provided with mortises therein, and a central opening for the 30 dial-spindle, of a dial-ring having a part provided with tenons to enter the mortises in the nose, screws passing through the dial-ring and engaging the nose, and a dial and dial-spindle,

the latter passing through the ring and nose and connected with the mechanism of the lock. 35

3. In a dial-lock, the combination with a lock-case having a mortised nose, and a tumbler-carrying gear having a threaded hub, of a dial-ring having a part provided with tenons adapted to enter the mortises in the nose, 40 screws passing through the ring and into threaded holes in the nose, a dial, and a screw-threaded spindle fixed to the dial and passing through the ring and nose and engaging the threaded hub of the tumbler-carrying gear. 45

4. In a dial-lock the combination with a lock-case having a mortised nose, and a tumbler-carrying gear having a threaded hub the latter having a key-groove therein, of a dial-ring having a part provided with tenons adapted to enter the mortises in the nose, screws passing through the ring and into threaded holes in the nose, a dial, a screw-threaded spindle fixed to the dial and passing through the ring and nose and engaging the threaded 55 hub of the tumbler-carrying gear, the said screw having a groove therein, and a key or wedge driven into the grooves in the hub and spindle, substantially as set forth.

In testimony whereof I have signed this 60 specification in the presence of two subscribing witnesses.

WARREN H. TAYLOR.
